US0D1033443S

(12) **United States Design Patent** (10) Patent No.: **US D1,033,443 S**
(45) Date of Patent: ** Jul. 2, 2024

(54) **DISPLAY SCREEN WITH A GRAPHICAL USER INTERFACE**

(71) Applicant: **Capital One Services, LLC**, McLean, VA (US)

(72) Inventors: **Erik Jay Salazar De Leon**, Richmond, VA (US); **Thomas Dohan**, Elmhurst, IL (US); **Jason Ferrell**, Glen Allen, VA (US); **Albert Berger**, Arlington, VA (US); **Vivian Wang**, McLean, VA (US); **Jennifer L Ellison**, New Kent, VA (US)

(73) Assignee: **Capital One Services, LLC**, McLean, VA (US)

(**) Term: **15 Years**

(21) Appl. No.: **29/791,191**

(22) Filed: **Jan. 4, 2022**

(51) LOC (14) Cl. **14-04**

(52) U.S. Cl.

USPC **D14/485**

(57) **CLAIM**

The ornamental design for a display screen with a graphical user interface, as shown and described.

DESCRIPTION

The sole FIGURE is a front view of an image of a display screen with a graphical user interface.

The broken line outline of a mobile device illustrates environmental structure of a display screen and forms no part of the claimed design. All other broken lines in the drawings depict portions of a graphical user interface that form no part of the claimed design.
